[57] CLAIM

The ornamental design for a heating windshield wiper shroud, as shown and described.

DESCRIPTION

FIG. 1 is a right end view of a heating windshield wiper shroud showing my new design; the left side view being a mirror image of that shown;

FIG. 2 is a top plan view thereof;

FIG. 3 is a bottom plan view thereof;

FIG. 4 is a right side view of the present design, the left side view being a mirror image of that shown; and,

FIG. 5 is a side perspective of the present design, the opposing side perspective being a mirror image of that shown.
